G. S. HERSHY

POWDER PUFF

Filed August 28, 1924

Patented Dec. 29, 1925.

1,567,503

UNITED STATES PATENT OFFICE.

GEORGE S. HERSHY, OF LOS ANGELES, CALIFORNIA.

POWDER PUFF.

Application filed August 28, 1924. Serial No. 734,633.

To all whom it may concern:

Be it known that I, GEORGE S. HERSHY, a citizen of the United States, residing at Los Angeles, in the county of Los Angeles and State of California, have invented new and useful Improvements in Powder Puffs, of which the following is a specification.

This invention relates to improvements in powder puffs.

10 It is an object of the invention to provide a powder puff in which there is disposed a suitable fibrous material adapted to receive the powder and evenly distribute it through the powder puff.

15 It is another object of the invention to provide an improved powder puff formed of two pieces of fabric which are stitched together around their edges, one of the pieces being formed of closely woven fabric which 20 is impervious to powder and the other piece being formed of loosely woven fabric permitting powder to be shaken therethrough.

25 It is a further object of the invention to provide an improved powder puff in which there is an opening permitting powder to be inserted into the powder puff, and to provide a suitable closure for the opening.

30 A still further object of the invention is to provide an injector for forcing powder into a powder puff and to provide means upon the injector for insuring the delivery of powder.

35 With the foregoing and other objects in view which will be made manifest in the following detailed description and pointed out in the appended claims, reference is had to the accompanying drawings for an illustrative embodiment of the invention, wherein:

40 Figure 1 is a front elevation, parts being broken away, of one form of the improved powder puff,

Fig. 2 is a vertical section taken substantially upon the line 2—2 of Fig. 1.

Fig. 3 is a perspective view of one form of closure which may be employed upon the powder puff shown in Figs. 1 and 2,

Fig. 4 is a horizontal section taken substantially upon the line 4—4 of Fig. 3,

Fig. 5 is a perspective view of another form of closure which may be used with the powder puff illustrated in Figs. 1 and 2,

Fig. 6 is a horizontal section taken substantially upon the line 6—6 of Fig. 5,

Fig. 7 is a front elevation of a modified form of the powder puff, parts being shown as broken away,

Fig. 8 is a vertical section taken substantially upon the line 8—8 of Fig. 7,

Fig. 9 is a front elevation of a still further modified form of powder puff, parts being broken away,

Fig. 10 is a vertical section taken substantially upon the line 10—10 of Fig. 9,

Fig. 11 is a vertical section of injector which may be employed to force powder into the interior of either of the improved powder puffs, shown as applied to a powder puff of the form as shown in Figs. 1 and 2, and

Fig. 12 is a side elevation, parts being broken away, showing a portion of the improved injector as applied to the powder puff illustrated in Figs. 7 and 8.

Referring to the accompanying drawings wherein similar reference characters designate similar parts throughout, the powder puff illustrated in Figs. 1 and 2 is formed of two pieces of fabric 10 and 11, which are stitched together around their edges to provide an inturned seam 12. An opening 13 is left in the seam 12 to permit the insertion of fibrous material 14, and a closure generally designated at 15 is provided therefor. In the preferred form, the piece 10 is preferably formed of a closely woven fabric which is 85 impervious to powder, such as closely woven soft velour. The piece of fabric 11 is formed of a loosely woven material which permits powder to pass therethrough from the interior of the puff to the exterior thereof and is preferably eiderdown, or equivalent material. The fibrous material 14 is preferably long fiber first cut wool which has a considerable spring and is capable of holding the powder within the interior of 95 the puff and evenly distribute it throughout the interior of the puff. Ordinary cotton or silk floss cannot be used for the fibrous material 14 and accomplish the same results as long fiber wool, for the reason that cotton and silk floss do not have the spring as in the wool and tend to pack and allow the powder within the interior of the puff to settle to the bottom.

As a means for introducing powder into 105 the interior of the puff, the opening 13 is provided with a suitable closure, enabling powder to be inserted therethrough and which will normally be retained in closed position. In Fig. 3, there is illustrated one 110 form of closure which may be employed. This closure constitutes two pieces of flexi-

ble rubber 18 and 19 which are held together by means of cement, as at 20. Loops 21 and 22 may be formed of ribbon and have their ends secured to the pieces 18 and 19, as 5 by rubber cement, or its equivalent. Pieces of ribbon 16 and 17 may be secured over the ends of the loops 21 and 22. The closure, as illustrated in Fig. 3, is inserted into the opening 13 and the edges of the pieces 10 of fabric 10 and 11 are stitched to the ends of the loops 21 and 22, or to the pieces 16 and 17, or to both. It will be readily understood that the pieces 18 and 19 of the flexible rubber are normally held, due to the 15 resiliency of the rubber, in a position shown in Fig. 4, so that the opening 13 is normally closed. When it is desired to introduce the powder into the interior of the puff, the loops 21 and 22 may be pulled 20 apart, separating the pieces 18 and 19 thereby forming a passageway from the exterior of the puff to the interior thereof. Upon the release of the loops 21 and 22, it will be readily understood that the pieces 18 and 25 19 spring back into their original position, as that shown in Fig. 4. In this manner the pieces 18 and 19 constitute a resilient spout or self-closing valve for normally maintaining the opening in closed position.

30 In Fig. 5 an alternative closure is disclosed. This closure consists of two pieces of sheet rubber 23 and 24 which have their side edges secured together as by cement 25. A single loop 26 has its ends secured to the 35 outer faces of the pieces 23 and 24 adjacent the top thereof. When this form of closure is inserted into the opening 13, the edges of the pieces of fabric 10 and 11 are secured to pieces of ribbon 27 and 28, which 40 are stitched to the ends of the loop 26. As will readily be understood, the pieces 23 and 24 may be pulled apart by the ends of the loop 26 to form a passageway from the exterior of the puff to the interior thereof, in a similar manner to the passageway 45 formed by the closure illustrated in Fig. 3. When the loop 26 is released, the resiliency of the pieces 23 and 24 will cause them to spring back to the position shown in Fig. 6, thereby closing the passageway formed between them.

50 The powder puff illustrated in Figs. 7 and 8 is formed of two pieces of material 10^a and 11^a, which are stitched together around their edges to form an inturned seam 12^a. An opening 13^a is formed in the seam 12^a, as before. As in the powder puff disclosed in Figs. 1 and 2, fibrous material 14^a, preferably of long fiber wool, is held between the pieces of fabric 10^a and 11^a, and the piece 10^a is preferably formed of closely woven velour, and the piece 11^a is preferably of eiderdown. As a means for closing the opening 13^a, stitches 30 formed of rubber 60 connect the edges of the pieces 10^a and 11^a in

the opening. When it is desired to admit powder to the interior of the puff disclosed in Figs. 7 and 8, the edges of the pieces 10^a and 11^a are merely pulled apart, thereby stretching the elastic stitches 30, as shown 70 in Fig. 12. Upon the release of the edges, the elastic stitches 30 will draw the edges together, thereby closing the opening 13^a.

The form of powder puff illustrated in Figs. 9 and 10 is made by stitching together 75 two pieces of fabric 10^b and 11^b, which may be of eiderdown and velour as before. These pieces are stitched together around their edges to form an inturned seam 12^b, and an opening, as at 13^b, is left in the seam 12^b. 80 Loops 21^b and 22^b may be secured to the edges of the pieces 10^b and 11^b in the opening 13^b. A rubber bag 40 is disposed within the powder puff and is of substantially the same size as the pieces 10^b and 11^b. This 85 rubber bag is adapted to contain fibrous material such as long fiber wool, as shown. Perforations 41 are formed in one side of the bag 40. A rubber spout 42 is inserted into an opening 43 provided in the bag 40 and secured thereto as by rubber cement. The spout 42 is adapted to receive a stopper 44. In this form of powder puff the stopper 44 is removed and powder poured or otherwise inserted through the spout 42 into the bag 40. By slapping the powder puff against the face, the powder will escape through the apertures 41 and be distributed evenly in passing through the piece of fabric 10^b. The powder puff may then be turned over and the piece 11^b may be employed to further distribute the powder upon the face without applying additional powder.

When the powder puff is provided with fibrous material, such as long fiber wool 14 and 14^a, it is necessary to force the powder into the interior of the puff. As a means for injecting powder into the puff, I have provided an injector, as illustrated in Fig. 11, which consists of a cylindrical barrel 50 preferably formed of glass and which is designed to hold the powder P. The lower end of the barrel 50 is reduced, as at 51, to provide a nozzle. A bulb 52 is secured within the barrel 50 having a portion 53 which fits within the barrel, which portion is provided with an aperture 54 permitting air to pass from the bulb 52 to the interior of the barrel 50 when the bulb is squeezed. It has been my experience that upon forcing powder P through the reduced nozzle 51, the powder frequently cakes together so that it sometimes becomes very difficult to force powder from within the barrel. I therefore provide a rod 55 which is secured to the top of the bulb 52 and which extends through the aperture 54. When the injector is inserted in the opening in the powder puff, as illustrated in Fig. 11, the bulb 52 is squeezed, thereby forcing air through the

- aperture 52 into the barrel 50 and urging the powder P through the nozzle. As the bulb is squeezed by pressing downwardly thereon, the rod 55 will pass downwardly into the nozzle 51, so that if any powder tends to cake within the nozzle 51, the rod 55 will loosen the powder and insure the delivery or discharge of the powder from the interior of the barrel 50.
10. When the rod 55 is passed through the nozzle 51 when the injector is discharging powder into a powder puff, the rod enters into the fibrous material, thereby forming an opening therein to receive the powder before it is shaken or distributed through the fibrous material. The rod 55 thus provides an opening in the fibrous material and facilitates the delivery of powder into the interior of the powder puff. If desired, wings may 20 be pivoted upon the rod 55 above the end of the rod which will force the powder down through the nozzle 51.
- It is to be understood that various changes may be made in the detail of construction 25 without departing from the spirit or scope of the invention as defined by the appended claims.
- I claim:
1. A powder puff having an opening formed therein, said powder puff having two pieces of material extending through said opening into the interior of the puff providing a self-closing means permitting the powder to be inserted into the puff and normally keeping the opening closed.
  2. A powder puff comprising two pieces of fabric stitched to each other around their edges, an opening formed between said pieces at their edges permitting powder to 40 be inserted between said pieces, a loop of ribbon secured in said opening, and self-closing means for closing said opening.
  3. A powder puff comprising two pieces of fabric stitched to each other around their edges, an opening formed between said pieces at their edges permitting powder to be inserted between said pieces, a loop of ribbon secured in said opening, self-closing means for closing said opening, and fibrous material disposed between said pieces 45 adapted to receive and evenly distribute powder.
  4. A powder puff comprising two pieces of fabric stitched together around their edges to provide an inturned seam, an opening formed in said seam permitting powder to be inserted between said pieces, a loop of ribbon secured in said opening, and a rubber spout secured in said opening, said spout being adapted to normally assume a flattened closed position so as to close said opening.
  5. A powder puff comprising two pieces of fabric stitched together around their
- edges to provide an inturned seam, an opening formed in said seam permitting powder to be inserted between said pieces, a loop of ribbon secured in said opening, a rubber spout secured in said opening, said spout being adapted to normally assume a flattened closed position so as to close said opening, and fibrous material disposed between said pieces adapted to receive and evenly distribute powder injected through said opening.
6. A powder puff comprising two pieces 75 of fabric secured together adjacent their edges forming an inturned seam, an opening formed in said seam, a closure for said opening consisting of two flat pieces of flexible rubber secured adjacent their edges to provide a normally closed opening therethrough, said pieces being secured in said opening in the seam and extending into the interior of the puff, the interior of said powder puff being filled with fibrous material.
7. A powder puff comprising two pieces of fabric secured together adjacent their edges forming an inturned seam, an opening formed in said seam, a closure for said opening consisting of two flat pieces of flexible rubber secured adjacent their edges to provide a normally closed opening therethrough, said pieces being secured in said opening in the seam and extending into the interior of the puff, the interior of said powder puff being filled with fibrous material, there being sections of ribbon secured adjacent the top of said closure for securing the closure to said pieces of fabric.
8. A powder puff comprising two pieces of fabric secured together adjacent their edges forming an inturned seam, an opening formed in said seam, a closure for said opening consisting of two flat pieces of flexible rubber secured adjacent their edges to provide a normally closed opening therethrough, said pieces being secured in said opening in the seam and extending into the interior of the puff, the interior of said powder puff being filled with fibrous material, and a loop of ribbon having its ends secured to said closure facilitating the separation of said pieces of rubber.
9. A powder puff having an opening formed therein, said powder puff having two pieces of material extending through said opening into the interior of the puff providing a self-closing means permitting the powder to be inserted into the puff and normally keeping the opening closed, the interior of the powder puff being filled with a fibrous material.
- In testimony whereof I have signed my name to this specification.

GEO. S. HERSEY.
